UNITED STATES PATENT OFFICE.

BERNHARD BRONNER, OF SYRACUSE, ASSIGNOR TO JESSE L. BRONNER, OF NEW YORK, N. Y.

UMBRELLA-STAND.

SPECIFICATION forming part of Letters Patent No. 499,449, dated June 13, 1893.

Application filed June 6, 1892. Serial No. 435,585. (No model.)

To all whom it may concern:

Be it known that I, BERNHARD BRONNER, of Syracuse, in the county of Onondaga, in the State of New York, have invented new and 5 useful Improvements in Lockers, of which the following, taken in connection with the accompanying drawings, is a full, clear, and exact description.

My invention relates to improvements in 10 lockers, particularly adapted for supporting umbrellas and similar articles, and has for its object the production of a simple, practical, and economical device, which may be placed in hotels, barber-shops, club rooms, halls, and 15 similar places visited for a short time by transient guests or others desiring to leave their umbrellas or similar articles in a secure place, whence they may be readily removed by them at will without any liability of loss or 20 change; and to this end the invention consists, essentially, in a frame, a trough for supporting a series of umbrellas and receiving their drip water, a series of compartments mounted above the trough for receiving the 25 handles of the umbrellas, hinged doors or walls for the several compartments provided with distinguishing characters as numerals, locks for securing the doors in position having their keys provided with distinguishing 30 characters corresponding to those of the doors, a stop in the several compartments for limiting the upward movement of the umbrellas, and in the detail construction and arrangement of the parts, all as hereinafter more particularly described and pointed out in the 35 claims.

In describing this invention, reference is had to the accompanying drawings, forming a part of this specification, in which like 40 letters indicate corresponding parts in all the views.

Figure 1 is a front elevation of one form of my improved invention. Fig. 2 is a horizontal sectional view, taken on line —2—2—, Fig. 45 1. Fig. 3 is a vertical sectional view, taken on line —3—3—, Fig. 1. Fig. 4 is a detail vertical sectional view, taken on line —4—4—, Fig. 1. Fig. 5 is a face view of the detached key No. 6 of my improved locker. Fig. 6 is a 50 vertical sectional view, taken on line —6—6—, Fig. 1. Fig. 7 is a longitudinal sectional view

of the inner end of one of the stop walls of a compartment of my locker, and Fig. 8 is a transverse vertical sectional view of a modified form of trough for my invention. 55

—A—represents the frame, which is of any desirable form, size, and construction to support the component parts of the locker and to conform to the character and style of the finish of the room provided therewith. 60

—B—represents a series of pockets or compartments —B'—, which are supported upon the lower portions or standards —a—a— of the frame —A—, and may also be of any desirable form, size, and construction, although 65 they are here shown as disposed in a horizontal tier, and as provided with bottom, top, back, and front walls —b—b'—b²—b³—. The bottom wall —b— is formed with a slot —b⁴— extending inwardly from its front edge, and 70 the front wall —b³— is hinged at —b⁵— to a partition —B²—, and is provided with a suitable lock —B³— for holding the movable wall in its closed position. The side walls of the 75 compartments or pockets are formed by the partitions —B²—, and the outer side walls —B⁴—B⁵— of the outer compartments are mounted directly above the standards —a—a.

—C—is a key-board or support, best seen in 80 Figs. 1 and 6, provided with a series of arms or lugs —c— formed with upturned outer ends —c'— and attaching ends —c²— preferably screw-threaded and provided with a stop shoulder —c³—. The number of these arms corresponds to the number of compartments 85 or pockets, and they become a convenient support for the various keys —K— of the locks —B³—, each of which is so constructed as to require a special key so that the holder of one can only unlock the movable wall —b³— 90 of the compartment provided with the corresponding lock.

In order to facilitate the use of the several compartments or pockets by different persons they are each provided with a distinguishing 95 character as a numeral, and the support —C— is also provided beneath each of its supporting arms with corresponding distinguishing characters.

—D—is a trough supported upon the standards —a—a—, beneath the series of compartments —B'—, and —d—d— are sockets above

the trough for receiving and supporting the lower ends of umbrellas or similar articles. The handles or the upper ends of the umbrellas are registered with the slots b^4 — in the lower walls of the compartments B' — directly above the sockets d —, and the movable doors or walls b^3 — of said compartments are then locked by the proper keys to the adjacent partitions B^2 —. It will be noted that the slots b^4 — in the lower walls of the compartments B' — are made sufficiently large to receive umbrella handles of the largest diameter, and that when the movable doors or walls b^3 — are in their normal position, their lower extremities extend downwardly beneath the plane of the tops of the umbrella handles, and prevent their removal therefrom. Each socket d — is preferably formed in a nipple d' — extending upwardly above the trough D — and having its lower end formed with screw threads engaged with a threaded socket D' — in the trough D —. The sockets d — are somewhat larger than the ends e — of the sticks E' — of the umbrellas E — and their lower ends are formed with laterally downwardly extending apertures d^2 — opening into the trough D — and for facilitating the passage of the drip water. I preferably arrange a second series B^6 — of compartments B^7 —, and support these in front, and above the compartments B' — upon the upper arms a' — a' — of the frame A —. These arms a' — a' — are formed with upper branches a^2 — a^2 — for supporting the back of the series B^6 — of the compartments B^7 —, and with the laterally extending branches a^3 — a^3 — for supporting the base of said series. The compartments B^6 — of this upper series are preferably of the same form and construction as the compartments B' — previously described, but are so arranged that the slots b^4 — in their lower walls b — are alternated with the corresponding slots b^4 — in the lower series of compartments.

Directly beneath the series B^6 — of compartments B^7 — is a second trough D^2 — of similar construction to the trough D —, and upon the standards a — a — are laterally extending arms a^4 — a^4 — for supporting this trough D^2 —. A suitable pipe F — connects the troughs D^2 — D — and conveys the drip water from the upper one to the lower.

As I have in the accompanying drawings shown two tiers B — B^6 — of compartments B' — B^7 —, and have stated that I prefer to use numerals as the distinguishing characters therefor I number the upper left hand compartment "1," and then each of the others consecutively until the right hand lower compartment is reached, and numbered "21." It will be observed that I do not number the two end compartments of the series B —, as these are somewhat smaller, owing to the alternate arrangements of the compartments of the upper and lower series, and may either

remain idle, or from their size and position may be readily distinguished by those having the keys therefor.

G — represents a series of stop walls for limiting the upward movement of the umbrellas, which, as preferably constructed, are movable in grooves b^6 — in the partitions B^2 —, so as to facilitate ready adjustment of the stop walls to the required height to limit the upward movement of the umbrellas having their handles supported in the separate compartments, and thus prevent disengagement of their lower ends from the sockets d —. It will thus be readily understood that an umbrella having its lower end engaged with a socket d —, and its upper end located in a compartment B' —, is safely secured within my improved locker, and can be removed only by unlocking the movable wall b^3 — of the compartment, thus entirely obviating loss or exchange of the umbrella.

When my improved locker is used in barber shops and similar places the keys for the various compartments are supported upon the arms c —, and a person having an umbrella and desiring to remain in the barber shop or similar place for a limited length of time removes any one of the keys, opens the door or movable front wall of the corresponding compartment, places his umbrella in position, as described, closes the compartment, and retains the key. When leaving he unlocks the compartment, removes his umbrella and replaces the key upon the support C —. Indeed even if he should neglect his umbrella it remains securely locked in its proper compartment, and can be removed only by the person having the proper key. I preferably make the compartments B' — B^7 — larger than necessary for receiving only the handle of an umbrella, as it is frequently desirable to use their upper portions for securing the rubbers or other articles of the umbrella owner from loss or exchange in the same manner that his umbrella is secured as just described. As the rubbers are usually wet and frequently muddy, the grooves b^6 — are inclined downwardly, and the lower end of the stop walls G —, which form a support for the rubbers are provided with perforations g — g —.

Directly beneath the perforations in the base of the compartments B' — B^7 — are the respective troughs B^8 — B^9 — for receiving the drip water discharged through perforations g — g — of the stop walls G — G — of said compartments. A pipe H — extends from the trough B^8 — through the partition of the lower series B — of compartments B' —, and conveys the water from said trough to the lower trough B^9 —, and a branch pipe B^{10} — conveys the water from the trough B^9 — to the pipe F — previously described. I preferably incline the troughs B^8 — B^9 — and D^2 — from their central portions downwardly toward their extremities, and use a pair of each of the pipes H —,

—B¹⁰—, and —F— for conveying the drip water from the opposite extremities of said troughs.

At Fig. 8 I have shown a slightly modified form of trough —T— somewhat deeper than the troughs —D—D²—, and in this case I provide the trough —T— with a top wall —T'— formed with a perforation —t— for receiving the lower end of the umbrella stick.

10 It will be readily understood that umbrellas, canes, and similar articles may be supported in my improved locker with great security and convenience, and that rubbers, gloves, or other articles may be secured in 15 like manner in the upper parts of its compartments.

My invention is simple in construction and its parts are readily manufactured and assembled, and, when completed, the lockers form 20 a handsome, ornamental, and useful article of furniture for the purpose described and for similar uses.

The detail construction and arrangement of the parts of my improved locker may, however, be greatly varied from the construction and arrangement described without departing from the spirit of my invention, as, for instance, only one series of compartments and a single trough may be used, or the compartments may be arranged in a circular instead of in a lengthwise plane as illustrated; hence I do not herein limit my invention to the precise construction of its component parts.

35 Having thus fully described my invention, what I claim as new, and desire to secure by Letters Patent, is—

1. In a locker, the combination of a frame, a normally closed compartment provided upon 40 the frame and formed with a lower wall having a slot for receiving the handle of an umbrella, a movable locking wall within the compartment for preventing upward movement of the handle, and a socket beneath the closed 45 compartment for receiving the lower end of the umbrella stick and limiting the downward movement of the umbrella, substantially as described.

2. In a locker, the combination of an open 50 frame or body, a series of normally closed compartments provided on the frame and each formed with a lower wall having a slot for receiving the handle of an umbrella, a series of partitions adjustably mounted in the separate 55 compartments for limiting the upward movement of the umbrella handles and supporting other articles, as rubbers, &c., placed thereon within the compartments, and a trough beneath the compartments for receiving the drip 60 water from the umbrellas, and limiting the downward movement of said umbrellas substantially as set forth.

3. In a locker, the combination of an open 65 frame or body, a series of normally closed compartments provided on the frame and each formed with a lower wall having a slot for receiving the handle of an umbrella, stops with-

in the compartments for limiting the upward movement of the umbrella handles, locking walls or doors for the separate compartments 70 for permitting the independent insertion and removal of the umbrella handles, and a support for the lower ends of the umbrella sticks, for limiting the downward movement of said umbrella sticks, substantially as specified. 75

4. In a locker, the combination of an open frame or body, a series of normally closed compartments provided on the frame and each formed with slots extending inwardly from the outer edges of their lower walls for receiving the handles of a series of umbrellas, locking walls or doors at the front side of each of the compartments having their lower extremities extended downwardly beneath the horizontal plane of the tops of the umbrella handles and movable upwardly to permit insertion and removal of said handles, and a support for the lower ends of the umbrella sticks, for limiting the downward movement of said umbrella sticks substantially as and 90 for the purpose set forth.

5. In a locker, the combination of an open frame or body, a series of normally closed compartments provided on the frame and formed with slots extending inwardly from the outer 95 edges of their lower walls for receiving the handles of a series of umbrellas, locking walls or doors at the front sides of the compartments having their lower extremities extended downwardly beneath the horizontal plane of the tops of the umbrella handles and movable upwardly to permit insertion and removal of said handles, and a trough beneath the compartments provided with upturned sockets for receiving the lower ends of the umbrella 100 sticks, and limiting the downward movement of the umbrella sticks said sockets being formed with outlet openings at their base discharging into the trough, substantially as described. 110

6. In a locker, the combination of a series of normally closed compartments provided with slots in their lower walls for receiving the handles of a series of umbrellas, movable partitions within the compartments for limiting 115 the upward movement of the handles, locking walls or doors at the front sides of the compartments provided with distinguishing characters as numerals, and locks secured to said walls or doors for locking the movable walls 120 in position and having their keys also provided with distinguishing characters corresponding with those on said movable walls or doors locking said compartment, substantially and for the purpose set forth. 125

7. In a locker, the combination of a series of normally closed compartments provided with slots in their lower walls for receiving the handles of a series of umbrellas, a movable partition within the compartments for preventing the upward movement of said handles, locking walls or doors for the compartments for permitting the insertion and removal of the handles, a trough beneath the 130

compartments for supporting and limiting the downward movement of the lower ends of the umbrella sticks and receiving the drip water from the umbrellas, a second series of closed compartments above the former compartments provided with slots in their lower walls for receiving the handles of a second series of umbrellas, movable partitions within the second series of compartments for preventing the upward movement of said handles of the second series of umbrellas, locking walls for the second series of compartments for permitting the insertion and removal of the second series of handles, and a trough beneath the second series of compartments connected to the former trough, for supporting and limiting the downward movement of the sticks of the second series of umbrellas substantially as and for the purpose set forth.

8. In a locker, the combination of an open frame or body, a series of normally closed compartments provided on the frame and formed with slots extending inwardly from the outer edges of their lower walls for receiving the handles of a series of umbrellas, and formed with stops for limiting the upward movement of the umbrella sticks a second series of compartments above the former formed with slots extending inwardly from the outer edges of their lower walls and arranged alternately with the slots in the lower series of compartments for receiving the handles of a second series of umbrellas, and

formed with stops for limiting the upward movement of the sticks of the second series of umbrellas, locking walls at the front side of the compartments of said series having their lower extremities extended downwardly beneath the plane of the tops of the umbrella handles, and movable upward to permit insertion and removal of said handles, and supports for the lower extremities of the sticks of said umbrellas, for limiting the downward movement thereof substantially as specified.

9. In combination, a trough for supporting a series of umbrellas and receiving their drip water, a series of compartments above the trough for receiving the handles of the umbrellas, a series of stop walls within the compartments for limiting the upward movement of the handles provided with perforations at their rear extremities, a trough beneath the perforated extremities of the stop walls, and a connection between said trough and the former trough, substantially as and for the purpose specified.

In testimony whereof I have hereunto signed my name, in the presence of two attesting witnesses, at Syracuse, in the county of Onondaga, in the State of New York, this 4th day of June, 1892.

BERNHARD BRONNER.
